UNITED STATES PATENT OFFICE.

JORDAN T. BRUMFIELD, DECEASED, LATE OF PORTLAND, OREGON, BY FRANCES D. BRUMFIELD, EXECUTRIX, OF PORTLAND, OREGON.

LOOSE-LEAF BINDER.

1,390,016.

Specification of Letters Patent. Patented Sept. 6, 1921.

Application filed October 23, 1919. Serial No. 332,690.

To all whom it may concern:

Be it known that JORDAN T. BRUMFIELD, late a citizen of the United States, residing at Portland, in the county of Multnomah and State of Oregon, has invented a new and useful Loose-Leaf Binder, of which the following is a specification.

His invention refers more particularly to that class of books in which the leaves are 10 perforated and inserted in loose leaf form.

The object of his invention is to provide an exceedingly simple and efficient means for holding perforated sheets in book form in quantities much greater than is possible 15 with the present appliances, and to do so in much better form, and at the same time rendering the addition or removal of any of the leaves a very simple operation.

He attained these results in the manner 20 described in the following specification and illustrated in the accompanying drawing.

Referring to the drawing. Figure 1 is a plan of the binder portion of the device showing it in locked position; Fig. 2 is a 25 front elevation of Fig. 1; Fig. 3 illustrates the device unlocked and the back moved out of the way preparatory to opening the binder; Fig. 4 is an end elevation of Fig. 3 showing the sheets in place and the binder 30 open.

Similar letters and numbers of reference refer to the same or similar parts throughout the several views.

Referring in detail to the drawing. A¹ is 35 a flexible back which is secured to the flexible cover A² to which is secured a pocket A³, if desired. A⁴ are perforated sheets which this device is intended to unite in book form.

H¹ is a base plate of thin metal which is 40 secured by means of the rivets H² to one edge of the flexible inner back A¹. This base plate H¹ is U shaped and holds the edge of the back A¹ between its members, the object being, of course, to furnish a flexible hinge for the base plate, this hinge being 45 supplied by the leather in the back A¹. On the base plate H¹ are pivotally mounted the two arms H³ whose pivots are formed by the lower ends of the standards H⁴. On the 50 swinging end of the pivoted arm H³ is mounted the swinging standard H⁵. The upper end of the pivoted standard H⁴ is supplied with a slot H⁶ which is adapted to receive the tongue H⁷ on the upper end of 55 the swinging standard H⁵, and the upper

ends of both of the standards being curved in a manner to form an approximate semi-circle when joined. The lower end of the swinging standard H⁵ is hinged to the swinging end of the pivoted arm H³ at the 60 joint H⁸.

It will be understood that the flexible inner back A¹ is secured to the back of the binder which is integral with the cover A². Only the edges of this flexible back are loose 65 and one side serves as a hinge for the base plate H¹ and the other side serves as a hinge for the cover plate L¹.

L¹ is a cover plate similar in size and mode of attachment to the flexible back as 70 is the base plate H¹ and is supplied with the slots L² adapted to receive a portion of the aforementioned semi-circle formed by the upper ends of the standards H⁴ and H⁵. Hooks L³ are rotatably mounted on the cover 75 plate L¹ in a manner that their tips may swing underneath the respective arches formed by the upper ends of the standards L⁴ and L⁵ as they pass through the slots L². The hook L³ is mounted on the pivot L⁴. 80

It will be observed in Figs. 1 and 2 that the arm H³ and its standards H⁴ and H⁵ are set at an angle to the cover plate L¹ corresponding to the angle of the slots L². However, when desiring to add or remove leaves 85 to or from this binder the pivoted arms H³ are moved into the position shown in Fig. 3, and the swinging standard H⁵ is swung back into the position shown in Fig. 4, which of course opens the binder and permits the de- 90 sired manipulation of the leaves.

While I have thus illustrated and described his invention it was not his intention to limit himself to this particular form or method of application, but intended that 95 it should cover all forms and modifications that fall fairly within the appended claims.

What he claimed as new and desired to protect by Letters Patent of the United States, is:

1. A loose leaf binder consisting of a base plate mounted on a hinge inside of a book back, a pair of wire arches mounted on said base plate, said arches adapted to be separated in a manner to admit perforated 100 sheets, a slotted cover plate also hinged to said book back adapted to fit over said arches sufficiently far to allow a portion of same to project through said cover plate, and hinged hooks mounted on said cover plate in 110

a manner to permit the tip of said hooks to pass between said arches and said cover plate when moving away from said cover plate hinge.

- 5 2. A loose leaf binder consisting of a cover member, a flexible back secured to the inside of said cover member, a base plate secured to one edge of said flexible back, a pair of swinging arms mounted on said base plate
- 10 at a distance equal to the distance between the perforations in the sheets, a standard mounted on each of said arms and forming its pivot, said standard having a curved upper end whose tip is supplied with a slot, a
- 15 swinging standard hinged to the swinging end of said swinging arm, said swinging standard having a curved upper end whose

tip is supplied with a tongue adapted to fit into the slot in the tip of said fixed standard, said standards when joined standing in a 20 parallel position and forming a semi-circle at their upper end, a cover plate secured to the edge of said flexible back member, said cover plate having slots adapted to receive the arch formed by said standards when 25 closed and said slot having a total length somewhat less than the total breadth of said arch, hook members pivoted on said cover plate in a manner to permit the tip of each hook to pass between said cover plate and 30 the projecting portion of one of said arches.

FRANCES D. BRUMFIELD.
Executrix of Jordan T. Brumfield, deceased.
